UNITED STATES PATENT OFFICE

CHARLES F. MEILINK, OF TOLEDO, OHIO

SPINDLE LOCK

Application filed October 24, 1929. Serial No. 402,017.

This invention relates to locking control. This invention has utility when incorporated in series with major or combination locks.

5 Referring to the drawing:

Fig. 1 is a fragmentary view of a safe having an embodiment of the invention incorporated therewith;

10 Fig. 2 is a view on an enlarged scale on the line II—II, Fig. 1, and

Fig. 3 is a section on the line III—III, Fig. 2.

Safe 1 is shown as having opening 2 in which is located door 3 swingable on hinges 15 to closed position at which handle 4 may be operated for throwing locking bolts 5 into position for retaining the door closed. This locking bolt mechanism as thrown into holding position when the door is closed may be 20 anchored in such position by plunger 6 entering recess 7 thus precluding any rocking of the handle 4 to unlocking position for the bolt mechanism or any attempt to withdraw locking bolt 5. The plunger 6 is thrust from 25 housing 7' carried within the door 3 by spindle 10 and positioned from the door front by sleeve 8.

In this housing 7' is series of tumblers 9 operable from shaft 10. Rotations of the 30 shaft 10 serve to assemble the tumblers 9 for the combination lock. As thus connected the shaft 10 is effective through arm or crank 11 for throwing plunger 6 into the seat 7 or withdrawing the plunger from such seat 7. This shaft 10 extends through the door 3 centrally of indicator plate 12 on the door front. This indicator plate 12 provides seat 13 in which is operable scale 14 carried by 35 spindle 15. This operating spindle 15 is freely operable or rotatable at all times to bring its graduations 14 into position with pointer 16 of the indicator plate 12.

Under the invention herein, this spindle 15 houses lock 17 having bolt 18 operable by 40 withdrawable key 19 insertable into the key-hole 20. This lock 17 is fast or fixed with the spindle 15 and is effective when its bolt 18 is thrown as a connector to connect this spindle 15 with cup extension 20' fast with 45 the shaft 10, so that this key may be with-

drawn and this spindle 15 be in the normal assembly for directly operating the tubular mechanism 9, in the housing 7' as may be usual in combination lock operations.

However, hereunder, the key 19 may be operated to withdraw the bolt 18 thereby allowing the spindle 15 to rotate relatively to the cup member 20'. This condition is permitted without the spindle becoming removable because nut 21 threaded into flange 22 on the inner side of the spindle 15 coacts with the enlarged cup 20' to hold this spindle 15 assembled with the shaft 10 although free to rotate relatively thereto. Furthermore, pressure exerted on the spindle 15 is not effective for any frictional gripping or holding action to be transmitted to the shaft 10 due to the physical independence therebetween, nor is it possible or practicable by any twisting or distortion of the spindle 15 to effect any rotation whatsoever of the shaft 10 except through the locking bolt 18, as registering in port 23 of the cup 20'.

It is accordingly seen that the key 10 may be withdrawn with the spindle 15 released so that no manipulation whatsoever is effective for unlocking the bolt mechanism by withdrawing the plunger 6. This rendering ineffective of the tumbler mechanism may even occur with the plunger 6 withdrawn. There is accordingly precluded any unauthorized tampering, either for locking or unlocking. This is a feature of exceptional value in chain store, theatre, filling station and like installations where many people may have casual access and it is desired to limit the control of the locking mechanism to one individual who is in possession of the key.

What is claimed and it is desired to secure by Letters Patent is:

In safe door locking equipment wherein there is a safe door, locking both mechanisms for the door, a lever handle for operating the mechanism, a combination lock for releasing the mechanism to permit operation of the lever handle, said combination lock having tumblers and a tumbler operating shaft through the door to the tumblers, the combination including said shaft of a combination lock spindle concealing the shaft, an in-

dex adjacent the spindle, and a key lock mounted concentrically of the spindle, said key lock being operable by the key to leave the spindle connected with or disconnected from the shaft, whereby with said shaft connected thereto, said spindle is operable relatively to the index to release the mechanism to permit movement of the lever handle to shift the door locking bolt mechanism to door unlocking position.

In witness whereof I affix my signature.
CHARLES F. MEILINK.

CERTIFICATE OF CORRECTION.

Patent No. 1,873,452.

August 23, 1932.

CHARLES F. MEILINK.

It is hereby certified that error appears in the printed specification of the above numbered patent requiring correction as follows: Page 1, line 92, for "both mechanisms" read bolt mechanism; and that the said Letters Patent should be read with this correction therein that the same may conform to the record of the case in the Patent Office.

Signed and sealed this 22nd day of November A. D. 1932.

(Seal)

**M. J. Moore,
Acting Commissioner of Patents.**
